No. 657,076.

Patented Sept. 4, 1900.

B. C. BATCHELLER.
CARRIER FOR PNEUMATIC TUBES.

(Application filed June 16, 1898.)

UNITED STATES PATENT OFFICE.

BIRNEY C. BATCHELLER, OF PHILADELPHIA, PENNSYLVANIA.

CARRIER FOR PNEUMATIC TUBES.

SPECIFICATION forming part of Letters Patent No. 657,076, dated September 4, 1900.

Application filed June 16, 1898. Serial No. 683,549. (No model.)

To all whom it may concern:

Be it known that I, BIRNEY C. BATCHELLER, a citizen of the United States of America, residing in the city and county of Philadelphia, 5 in the State of Pennsylvania, have invented a certain new and useful Improvement in Carriers for Pneumatic Tubes, of which the following is a true and exact description, reference being had to the accompanying drawings, 10 which form a part thereof.

My invention relates to the construction of carriers for pneumatic tubes, having for its object to provide a carrier of simple and efficient construction and in which particular 15 provision is made, first, for the tight closing of the carrier so as to exclude water; second, for an effective and secure attachment of an electrical contact-plate to the carrier; third, for the provision of a lid or door constructed 20 so as to form a tight joint with the carrier when closed and at the same time to leave the charging end of the carrier unobstructed when opened, and, fourth, I aim to provide a simple and effective locking device for the lid of 25 such character as to insure the proper locking of the lid to the carrier-body before it is inserted in the tube.

The nature of my improvements will be best understood as described in connection 30 with the drawings in which they are illustrated, and in which—

Figure 1 is a side sectional elevation of a carrier provided with my improvements. Fig. 2 is a view of the lid end of the carrier, showing 35 the lid in and locked to place. Fig. 3 is a view of the front end of the carrier. Fig. 4 is an elevation, partly in section, of the socket-piece used in connection with the front end of the carrier. Fig. 5 is a similar sectional elevation taken at right angles to the section 40 shown in Fig. 4. Fig. 6 is a perspective view of the plate-latching device used in connection with the socket-piece. Fig. 7 is a perspective view of the contact-plate, and Fig. 8 is a cross-sectional view taken as on the line 45 $\alpha\alpha$ of Fig. 5.

A indicates the side walls of the carrier, which is conveniently made of sheet metal.

B B are the contact-rings, secured around 50 the walls of the carrier.

C is a conical seat secured on the inside of the rear end of the carrier.

As shown, D is a block secured by rivets to the walls of the carrier inside of the seat C and serving to support the hinge E, to which 55 is attached a hinge-bar E', connected at its outer end by another hinge E² with the lid or cover indicated at F and which is preferably made with outwardly-flaring conical walls (indicated at F') and terminating in an 60 outwardly-turned flange F², adapted to extend to the walls of the carrier.

F³ is an annular plate secured on the inside of the lid F and serving, in connection with the flange F², to support and secure in place 65 a packing-ring G, which fits against the conical seat C of the carrier-body.

H is a pivot-pin secured eccentrically to the lid F, so as to turn therein, and having attached to it, as shown, an eccentric I, which 70 fits in a slot J', formed in the outer end of a plate J, which plate is pivoted at or near the center of the lid on a pin K, and has pivotally attached to it at points L L, &c., substantially equidistant from the pin K, locking-bolts M M, 75 &c., which extend through the wall F² of the lid, in which perforations f are formed for that purpose, into convenient corresponding recesses formed in the seat C.

H' is a handle preferably formed of a spring-plate and secured to the pin H, as shown, in such a way that when it is turned to a position in which its outer end lies within the territory of the carrier the bolt M will be shot and preferably the outer end of the handle sprung 85 down, so that it will lie inside of the walls F' of the lid.

It will be noticed that in this construction the double-hinged connection of the lid and carrier-body is such as will enable the lid to 90 be moved when opened, so as to leave the open end of the carrier unobstructed, and also that the double hinging enables the lid to be inserted like a cork or plug into the end of the carrier, fitting down snugly on the conical seat C, and thus facilitating the making of a water-tight joint. During the opening and closing of the lid the handle H' must be moved to a position which will, acting through the pin H, eccentric I, and plate J, withdraw 95 the bolts from locking engagement. In this position the handle H, being eccentrically pivoted to the lid, will extend out beyond the walls of the carrier to such an extent as to

offer an obstruction to the insertion of the carrier in a pneumatic tube. It is necessary, therefore, not only to lock the lid in place, but to enable the carrier to be inserted in the tube, that the handle should be moved to a position which will shoot the bolts and lock the lid, and owing to the nature of the connection between the lid and the carrier it is obviously impracticable to move the handle to a position which would indicate that the bolts are shot unless the bolts are actually shot and home in the recesses provided for them in the conical seat.

Turning next to the forward end of the carrier, N is a dish-shaped plate secured to the front end of the walls of the carrier in such a way as to form a tight joint therewith, such joint being indicated at N' and at N², the edge of the plate N being represented as turned over the end of the walls of the carrier. At or near the center of the plate N, I prefer to form a recess N³, as indicated, and for my special construction I form an opening, as indicated at n³, through the plate.

25 O is a socket-piece threaded at its inner end and adapted to pass through the perforation n³ and to be held therein, as by means of a nut O⁶. The socket-piece is formed with a recess O' and enlarged at its outer end, as indicated at O², the enlarged portion having a slot-like passage O³ leading through its outer face and opening into an enlarged recess O⁴, which may be of annular form and below which lies an elongated opening O⁵, into which 35 the opening O' leads, as shown.

P' indicates the "shank," so to speak, of a latch-piece, which is formed with a slot P² and an elongated head P⁴, transversely slotted, as indicated at P⁵.

40 U is a spring which is inserted in the opening O' of the socket-piece and upon which rests the shank P' of the latch-piece, P⁸ indicating a pin passing through the socket-piece and the slot P² of the latch-piece and 45 serving to hold the latch-piece in position, as indicated in Figs. 4 and 5, against the thrust of the spring U.

S is a shank attached to the under side of a contact-plate S' and provided at its inner 50 end with an elongated section S², S³ indicating a longitudinal perforation extending through the contact-plate and shank and preferably made of rectangular form, as indicated.

O⁷ indicates an annular metal plate secured on the portion O² of the socket-piece, as shown in Fig. 1, and which serves to support what I will call the "end pad" of the carrier, which, as shown, is made up of annular disks of leather, as indicated at Q, Q' indicating rivets holding the outer end of these disks together, and Q² rivets by which they are secured to the plate O⁷. Between the pad Q and the plate N is a packing of elastic material, such as wool, (indicated at T,) and N⁴ indicates a cap-piece secured to the inside of the plate N and forming a tight joint therewith.

It will be obvious that by the construction described the outer end of the carrier is made elastic, so as to yield to any shock to which it may be exposed by impact, while at the same time the interior of the carrier is protected from the entry of any water through the elastic head by the tight joint formed between the plate N and the walls of the carrier and the tight cap N⁴, extending over the perforated center of the plate N².

What I have referred to as the "contact-plate" is a device for making electrical contact with devices used in connection with the pneumatic-tube system, and I contemplate the use of a series of contact-plates of differing diameter each adapted to make contact with electrical terminals arranged at different distances from each other at different parts of the system. Consequently it is necessary that the carrier should be readily equipped with a contact-plate corresponding to the particular part of the system to which it is intended to be delivered and that these plates should be readily interchangeable. This can readily be provided for by making the plates S' of varying diameter; but preferably I use the plate S' simply as a holder for the contact-plate proper, which is indicated at R, formed with a central perforation for the passage of the shank S and with a recess, as indicated at R', for the plate S'. Where the plate S' is used alone or with the supplemental contact-plate R, it is obvious that it can be inserted in the socket-piece and that the end piece S² will on insertion rest against the end piece P⁴ of the latch lying transversely across the slot P⁵. By pressing the plate S' and its attachments inward the latch-piece P' P⁴ is also pressed inward, and by turning the plate S' and its attachments the portion S² will assume a position transverse to the perforation O³ and be engaged by the slot P⁶ in the latch-piece, and thus be securely held in position. In order to remove it, it is necessary to insert a key through the opening S³, pressing the latch down until its slot P⁶ is disengaged from the portion S² of the contact-plate or contact-plate-locating device, whereupon said device may be turned into registry with the slot O³ and withdrawn.

While the particular latching device for contact-plates which I have shown and described is one at once simple and effective, I believe I am the first to provide an automatic spring-latch to engage and hold contact-plates in position upon the carrier, and I do not therefore desire to be understood as limiting myself to the particular mechanism shown except in those claims where its detailed construction is specifically referred to.

Having now described my invention, what I claim as new, and desire to secure by Letters Patent, is—

1. A carrier for pneumatic tubes having at its front end a spring-actuated latching device in combination with a contact-plate adapted to be engaged and locked on the

front end of the carrier by said latching device.

2. A carrier for pneumatic tubes having at its front end a spring-actuated latching device in combination with a contact-plate adapted to be engaged and locked on the front end of the carrier by said latching device, and a keyhole leading to the latching device whereby a key can be inserted to unlock it.

3. A carrier for pneumatic tubes having at its front end an opening for the insertion of the shank of a contact-plate and a spring-actuated latch adapted to engage said shank in combination with a contact-plate having a shank adapted to enter said opening and engage said latch, and a keyhole formed through it whereby a key can be inserted to disengage the latch.

4. A carrier for pneumatic tubes having at its front end a socket, as O², having an elongated opening O³, circular space O⁴ and spring-chamber O⁵, in combination with a latch P' having a head P⁴ lying in space O⁴ and slot P⁴ formed in said head to lie transversely to the opening O³, a spring arranged to press said latch outward, a contact-plate and a shank S having a cross-piece S² at its end for securing the plate in the socket as described.

5. A carrier for pneumatic tubes having at its front end a fixed plate N forming a tight joint with the sides of the carrier and formed with a perforation n³, in combination with a socket O² extending through said perforation and secured to the inside of the plate N as by nut O⁶, an end pad as Q secured to the outer end of the socket, an elastic padding T between the end pad and the plate N, and a tight cap N⁴ secured on the inside of the plate N as and for the purpose specified.

6. A carrier for pneumatic tubes having a conical lid-seat in combination with a lid having a conical flange as F' with outwardly-extending packing-retaining flanges F² F³ and 45 an elastic packing-ring situated on flange F' between flanges F² F³, a hinge-bar as E' and hinges E, E², connecting said bar with the side of the carrier and with the lid respectively. 50

7. A lid for pneumatic carriers having a substantially-central pivot, as K, in combination with a plate J pivoted thereon at one end and having a series of bolts M M, &c., pivotally connected thereto and a slot as J' formed in the other end of plate J, a pin H secured eccentrically to the lid so as to turn therein, an eccentric I secured on said pin so as to lie in and engage slot J' and a handle H' secured to said pin H as described and so as to lie within 60 the periphery of the carrier only when turned to a position in which the bolts M M, &c., are shot.

8. A lid for pneumatic carriers having outwardly-extending walls F and a substantially-central pivot, as K, in combination with a plate J pivoted thereon at one end and having a series of bolts M M, &c., pivotally connected thereto and a slot as J' formed in the other end of said plate J, a pin H secured eccentrically to the lid so as to turn therein, an eccentric I secured on said pin so as to lie in and engage slot J' and a spring-handle H' secured to said pin H as described and so as to lie within and below the periphery of the 75 walls F' only when turned to a position to shoot the bolts M M, &c.
